TUBULAR BOILER

Arthur P. Victor, Minneapolis, Minn., assignor of
one-half to Herman E. Victor, Minneapolis,
Minn.

Application February 3, 1938, Serial No. 188,472

2 Claims. (Cl. 122—265)

My invention relates to boilers and has for an object to provide an extremely simple and practical boiler particularly adapted for use for heating purposes.

5 Another object of the invention resides in providing an extremely compact construction which can be erected at a minimum expense.

Another object of the invention resides in providing a highly efficient boiler and one where the 10 heating medium can be quickly brought up to the desired temperature.

A still further object of the invention resides in providing a boiler which can be readily used for coal, gas or liquid fuels.

15 Another object of the invention resides in constructing the boiler with two heat exchange members, each having one or more elongated passageways and in arranging said member one above the other within the boiler.

20 Another object of the invention resides in arranging the uppermost heat exchange member with its passageway substantially horizontal and the lower heat exchange member with its passageway inclined from a position above the fire 20 door at the front of the boiler downwardly toward the rear of the boiler.

A feature of the invention resides in connecting 30 said upper heat exchange members at the rear end of the same to said lower heat exchange member at the lowermost portion thereof and at its rear end, and in providing an inlet connected to the other end of the upper heat exchange member, and an outlet connected to the other end of the lower heat exchange member.

35 Another feature of the invention resides in constructing said heat exchange member with banks of tubes connected to manifolds open at their outer faces and in providing cover plates secured to the open portions of said manifolds exteriorly 40 of the boiler for closing the same.

45 Other objects of the invention reside in the novel combination and arrangement of parts and in the details of construction hereinafter illustrated and/or described.

In the drawing:

Fig. 1 is a vertical sectional view of a boiler illustrating an embodiment of my invention.

Fig. 2 is a rear elevational view of a portion of 50 the boiler shown in Fig. 1.

Fig. 3 is a plan sectional view of the boiler shown in Fig. 1 and taken on line 3—3 of Fig. 1.

55 My invention may be used with different types of boiler settings and for the purpose of illustration a particular type of setting has been shown

in the drawing with which the invention is particularly adaptable.

The construction, illustrated, comprises an ash pit section 10, a fire box section 11 and a combustion chamber section 12. All of these parts are 5 supported within a frame work 13 and are separately renewable in case of wear or in case the same become otherwise disqualified for use. Within the combustion chamber section 12 is arranged the heat exchange unit, which is indicated in its entirety by the reference numeral 14. This heat exchange unit comprises an upper heat exchange member 15 and a lower heat exchange member 16. These various parts will now be 10 described in detail.

15 The ash pit section 10 comprises a rectangular casting 17 open at the top and bottom and constructed with a rear wall 18, side walls 19 and with vertical flanges 21 extending upwardly along the forward portions of the side walls 19 and 20 forming an ash pit opening 22 at the forward portion of the same. Attached to the outer surfaces of the flanges 21 is a plate 23 which is provided with an ash pit doorway 24 closed by an ash door 25. The door 25 may be mounted on 25 the plate 23 in the customary manner. Such construction forms no particular feature of the invention and has not been shown in the drawing.

The ash pit section 10 supports the grates of 30 the invention in the following manner. Extending about the walls 18 and 19 and flanges 21, of the casting 17, is a ledge 26, which is near the upper edges of the same. This ledge carries two longitudinally extending plates 27 which are 35 formed with inwardly projecting flanges 28. Resting on the flanges 28 and upon the ledge 26, of the rear wall 18, is a similar plate 29. A corresponding plate 31, at the forward portion of the casting 10, is supported solely on the flanges 28 40 of the plates 27. The plates 27 and 29 overlie the upper edges of the walls of the casting 17 and are rabbeted, as indicated at 32 to fit the same.

The grates of the invention comprise two stationary grate plates 33 and 34 which are positioned adjacent the plates 29 and 31. These plates are constructed with openings 35 through which the air may pass. Between these plates are two rocking grates 36 and 37 which are provided at their ends with trunnions 38. Trunnions 38 fit into notches 39 in the flanges 28 and are thus supported for rocking movement.

The two grates 36 and 38 are provided with depending arms 41, as best shown in Fig. 1. These arms are connected together by means of a link 55

42. Another link 43 is connected to the arm 41 of grate 36 and to an arm 44 of a shaker lever 45. Shaker lever 45 includes a shaft 46 which extends through one of the walls 19 of the casting 17 and is journaled in a boss 47 formed therein. The lever 45 is provided with a handle 48 by means of which the same may be manipulated.

It will be noted that the fixed grates 33 and 34 are of substantially the same width as the 10 rocking grates 36 and 37 and notches 29 are provided centrally with respect to the space occupied by these grates so that other rocking grates may be substituted in place of the fixed grates, if desired. When the grates are properly installed 15 the upper surfaces of the same and the plates 27, 29 and 31 all lie in a common horizontal plane.

The frame 13, of the invention, consists of four 20 uprights 51, 52, 53 and 54 which are angular in cross section and are bolted to the casting 17 at the corners thereof. These uprights have secured to the upper ends of the same cross frame members 55 which are mitered at the corners and riveted to said vertical uprights.

The fire box section 11, of the boiler, is constructed 25 from fire brick, indicated at 56, which is laid in courses with the joints staggered. Where standard sizes of brick are used, six courses are employed at the front and sides, and an extra course indicated at 57 utilized at the rear of the fire box section 11. These brick may be laid flat, as shown, where desired. The brick if preferred 30 may be laid on edge, in which case less courses are required.

The combustion chamber section 12 is constructed 35 from four sheets of asbestos mill board 61, 62, 63 and 64 which are disposed within the uprights 51, 52, 53 and 54 and are bolted or otherwise secured thereto. This asbestos mill board is of sufficient thickness to give the desired insulating effect and to confine the heat within the 40 boiler. A metal plate 65 is secured to the upper flanges of the angle frame members 55 and carries a thimble 58 to which a smoke pipe 59 is secured. This plate may be bolted or otherwise 45 secured to the angle frame members 55.

In the sheet 62 of mill board is provided an opening 66, at the lowermost portion of the same, and in which is inserted a fire door frame 67 which has an opening 68 in it. This frame is 50 constructed with flanges 69 and 71 at the sides and top which snugly fit against the edges of the mill board formed by the opening 66. The said frame further includes a ledge 72 which rests upon the upper course of brick forming the fire 55 box section 11. The frame 67 is further constructed with a flange 73 which overlies the outer surface of the sheet of mill board 62 and is secured thereto and to the two angles 51 and 54. A door 74, hingedly mounted on the frame 67, closes 60 the opening 68 through said frame. Inasmuch as the construction for mounting the door does not form any particular feature of the instant invention, the same has not been illustrated in the drawing.

65. The heat exchange unit 14, as previously stated, consists of two heat exchange members 15 and 16 which will now be described in detail.

The heat exchange member 15 comprises two 70 box-like manifolds 75 and 76 which are identical in construction and are constructed with inner walls 77, upper and lower walls 78 and 79 and end walls 81. These manifolds are open at the outer portions thereof opposite the inner walls 77. A flange 82 encircles each of the manifolds at the 75 open portion thereof and is formed at the outer

ends of the walls 78, 79 and 81 and is adapted to overlie the uprights 51, 52, 53 and 54 and the sheets of mill boards 61 and 62. Suitable openings 83 and 84 are formed in the sheets of mill board 61 and 62 to receive these manifolds which 5 project inwardly into the combustion chamber 12, as clearly shown in Fig. 1. Between the two manifolds 75 and 76 are provided a number of tubes 85 which extend through the walls 77 and are swedged at their ends to form a tight joint 10 with said walls. These tubes form a bank of tubes which bring the two manifolds into communication. Plates 86 and 87 are bolted to the flanges 82 of the manifolds 75 and 76 and close the outer open portions thereof. 15

The heat exchange unit 14 is constructed similar to the heat exchange unit 15 and comprises two manifolds 88 and 89 which are identical in construction, excepting that the same are arranged in inverted relation with respect to one 20 another. These manifolds are triangular in cross section and are constructed with inner walls 91, lower or upper walls 92 and end walls 93. A flange 94 encircles the walls 91, 92 and 93 and serves the same purpose as the flanges 82 of the 25 heat exchange member 15. The entire heat exchange member 14 is arranged on an incline, as shown in Fig. 1, sloping from a position above the fire door frame 67 and in proximity to the heat exchange member 15 to a position immediately 30 above the course of brick 57 at the rearward portion of the fire box section 11. Due to the construction of the manifolds 88 and 89, of triangular cross section, such arrangement is made possible and the flanges 94 caused to overlie 35 the sheets of mill board 61 and 62 and the uprights 51, 52, 53 and 54. Between the walls 91 of the manifolds 88 and 89 are provided tubes 95 which are secured to said walls in the same manner as the tubes 85 and serve the same purpose. 40 Plates 96 and 97 are attached to the flanges 94 and close the open portions of said manifolds.

The manifold 89 is supported on a small angle 98 which is attached to the uprights 51 and 54. The flange 82, of manifold 76, rests upon the 45 flange 94 of manifold 89 and is supported thereby. The manifolds 75 and 88 are similarly supported on angles 101 and 102 which are attached to the uprights 52 and 53. To form a tight joint between the flanges 82 and 94 and the respective 50 sheets of mill board which they overlie, fillers 103 constructed of asbestos of the same thickness as the flanges of the uprights 51, 52, 53 and 54 are utilized which are held between said flanges and sheets of mill board, and which bring the flanges 55 flush with the outer surfaces with the uprights 51, 52, 53 and 54. If desired, the manifolds 75, 76, 88 and 89 may be secured to the sheets of mill board and the uprights supporting the same. I have found, however, that this is unnecessary 60 for when the parts are unattached a certain amount of freedom is given which permits of expansion of heat exchange members, independently of the boiler proper, without causing undue leakage. 65

The manifold 75 is connected to the manifold 88 by means of two pipes 104 and 105. These pipes have secured to the ends thereof, flanged elbows 106 and 107 which are bolted to the plates 86 and 88. These elbows communicate with the 70 interiors of the said manifolds by means of openings in the plates 86 and 88, not shown in the drawing. The two manifolds 75 and 88 have connected to them pipes 108 and 109 which have secured to the ends thereof flanged elbows 111 and 75 112.

112. These elbows serve the same purpose as the elbows 106 and 107 and bring the pipes 108 and 109 into communication with the chambers in the manifolds 76 and 89. The pipe 108 serves as an inlet pipe and the pipe 109 serves as an outlet pipe for the boiler.

5 Within the interior of the combustion chamber section 12 is provided a beveled ledge 113, constructed of some suitable plastic ceramic material, which extends from the upper course of brick to the inner surfaces of the sheets of mill board 61, 62, 63 and 64. A similar ledge 114 is laid upon the upper course 57 of brick and extends up to the lower wall 92 of the manifold 88. 10 In this manner pockets for the accumulation of 15 soot and fuel are prevented. Upon the upper portion of the heat exchange unit 14 is placed a baffle 115, constructed of asbestos mill board, similar to the walls of the combustion chamber. 20 Another baffle 116, similarly constructed, is laid upon the heat exchange member 15. Both of 25 these baffles are shorter than the tubes on which they rest and by means of the same the interior of the combustion chamber section 12 is divided 30 into a combustion chamber proper, indicated at 117, an intermediate chamber 118 and a smoke box chamber 119. Due to the fact that the baffles 115 and 116 are shorter than the tubes on which they rest, passageways 121 and 122 are formed which bring these various chambers into communication.

The method of utilizing the invention is as follows. The boiler is installed and connected to the chimney through the smoke pipe 59 in 35 the customary manner. Pipe 108 is connected to the return of the steam or water system with which the boiler is to be used. Pipe 109 is connected to the feed pipes of the system. When the boiler is fired in the customary manner, the 40 heated gases generated in combustion chamber proper 63 rise and heat is transferred to the tubes 95. The gases of combustion pass upwardly through the passageway 121 and enter chamber 118 where additional heat is absorbed by the 45 tubes 85. The gases of combustion finally leave this chamber through passageway 122 and enter the smoke box chamber 119 where the same pass out through the smoke pipe 59 to the chimney of the building in which the boiler is installed. In 50 this manner, the hot gases come in contact with two heat exchange members and a greater portion of the heat of the said gases is absorbed.

The advantages of my invention are manifest. An extremely simple and practical construction 55 is provided which produces highly effective results and is extremely efficient. By constructing the tubes of the heat exchange members of copper, rapid transfer of heat occurs and changes of temperature in the fire box are rapidly transmitted to the heat exchange members. By the 60 arrangement of heat exchange members rapid circulation of the heat exchange fluid is procured. At the same time, a minimum amount of space is occupied by the heat exchange members and the chambers constituting the combustion chamber are maintained relatively small so that the heat is readily transferred to the heat ex-

change members and a minimum amount of heat through the exterior walls of the boiler. I have found that, a boiler constructed, in accordance with my invention, of considerably smaller dimensions than boilers heretofore used, can be employed to heat buildings of the same size. I have further found that considerably less fuel is required than with ordinary boilers to procure the same heating effects.

5 While I have shown the boiler as adaptable for use with coal or solid fuel it can readily be comprehended that the boiler may be built to utilize gas or liquid fuel by the adoption of suitable gas or oil burners and the boiler changed in the necessary respects to adapt it to such uses.

10 Changes in the specific form of my invention, as herein disclosed, may be made within the scope of what is claimed without departing from the spirit of my invention.

15 Having described my invention, what I claim as new and desire to protect by Letters Patent is:

20 1. In a boiler, a wall structure providing a heat exchange chamber and including front and rear walls, a manifold in said front wall near the upper portion thereof, a second manifold in the 25 rear wall opposite said first manifold, a third manifold in said front wall disposed immediately below said first manifold and in juxtaposition with respect thereto, a fourth manifold in said rear wall disposed beneath said third manifold 30 and spaced therefrom, said manifolds extending through said walls and into said heat exchange chamber, a bank of tubes between said first and second manifolds and extending in a substantially horizontal direction, a bank of tubes between 35 said third and fourth manifolds and extending in an inclined direction, the aggregate cross sectional area of the tubes of both banks being substantially equal, a conduit connected to said second and fourth manifolds, an inlet directly connected to said first manifold and an outlet directly connected to said third manifold.

40 2. In a boiler, a wall structure providing a heat exchange chamber and including front and rear walls, a manifold in said front wall near the upper portion thereof, a second manifold in the 45 rear wall opposite said first manifold, a third manifold in said front wall disposed immediately below said first manifold and in juxtaposition with respect thereto, a fourth manifold in said rear wall disposed beneath said third manifold 50 and spaced therefrom, said manifolds extending through said walls and into said heat exchange chamber, a bank of tubes between said first and second manifold and extending in a substantially horizontal direction, a bank of tubes between 55 said third and fourth manifolds and extending in an inclined direction, the aggregate cross sectional area of the tubes of both banks being substantially equal, a conduit connected to said second and fourth manifolds, said conduit being disposed exteriorly of said wall structure, an inlet directly connected to said first manifold, and an outlet directly connected to said third manifold.

60
